UNITED STATES PATENT OFFICE.

WILLIAM J. BITTER, OF TOLEDO, OHIO.

ROSETTE FOR BRIDLES.

SPECIFICATION forming part of Letters Patent No. 339,848, dated April 13, 1886.

Application filed May 19, 1884. Renewed March 12, 1886. Serial No. 195,039. (No model.)

To all whom it may concern:

Be it known that I, WILLIAM J. BITTER, a citizen of the United States, residing at Toledo, in the county of Lucas and State of Ohio, have invented new and useful Improvements 5 in Rosettes for Harness-Bridles, of which the following is a specification.

My invention relates to rosettes for bridles and other parts of harness, and has for its 10 object to simplify and cheapen the construction thereof, and at the same time to render the same strong, durable, and attractive; and it consists in the construction and combination of parts, hereinafter particularly described, and pointed out in the claims, reference being had to the accompanying drawings, in which—

Figure 1 is a bottom perspective view with one end of the loop-bar detached; Fig. 2, a 20 bottom plan view with both ends of the loop-bar attached; Fig. 3, a front elevation, partly in section; and Fig. 4, a central sectional view on the line $x-x$, Fig. 2.

In the drawings, the letter A designates 25 the front plate or cap of the rosette stamped, struck up, punched, or spun from a single piece of metal of any desired configuration, and with a circumferential flange, a, having lips a'. Within this cap, with its outer edge 30 fitting close to the sides of the flange a, there is fitted a back plate, B, also struck up, punched, or otherwise formed from a single piece of metal or other suitable material, and made with a circumferential flange, b, which 35 flange will fit close to the flange a of the cap A, as seen in Fig. 4. This plate is held to the cap by overlapping the lips a' over onto its outer face, as seen in Fig. 1. It will be observed that the two parts thus formed are 40 simple and strong, and that they can be readily connected and disconnected.

The rosette is provided with a loop-bar, C, for its attachment to the desired part of the harness, which bar is formed with bent ends 45 c, and can be easily attached and detached after the two plates have been put together, if necessary. To admit of the attachment of this bar to the rosette, the back plate, B, is formed at one point with a hole, d, and at another point 50 with an angular slot, t, which is preferably L-shaped, as shown, with the long arm thereof preferably curved in the arc of a circle, so

as to permit one end of the bar to move therein in the arc of a circle. If desired, the terminus of said slot in which the end of the bar rests 55 may be slightly enlarged, as shown. Instead of curving said slot in the arc of a circle, the same may be made wide enough to permit the bar to be moved and describe such an arc, as is obvious. Along one edge of the slot there is 60 formed a catch or tang, s, which may be turned down to lock the bar in place, as seen in Figs. 1 and 3.

The bar is attached by passing one end through the hole d, and then lowering the 65 other end so that its bent portion will pass through the short arm of the slot, which brings it under the plate, after which the bar is turned until the bent end passes the tang s, when the latter is turned down and the bar securely 70 held and locked to its place.

The manner of applying the loop-bar is not only simple, but it admits of the bar being attached and detached after the cap and back plate have been secured together.

Having thus described my invention, what I 75 claim is—

1. The combination, with the cap and the back plate formed with an angular slot, of the 80 detachable loop bar having bent ends, and secured to the plate by one end passing through the plate and the other end fitting in the angular slot, substantially as described.

2. The combination, with the cap and the back plate formed with an angular slot, of the 85 detachable loop-bar having bent ends, and secured to the plate by one end passing through the plate and the other end through the angular slot, and a tang to cross said slot to lock the bar therein, substantially as described. 90

3. The combination, with the cap and the back plate formed with an angular slot, of a pivoted loop-bar having one end fitted in said slot, so as to move therein in the arc of a circle, and a catch to confine the bar in said slot, 95 substantially as described.

In testimony whereof I have hereunto set my hand in the presence of two subscribing witnesses.

WILLIAM J. BITTER.
